(57) **CLAIM**

The ornamental design for a catching device, as shown and described.

DESCRIPTION

FIG. 1 is a perspective view of a catching device showing my new design;

FIG. 2 is a top plan view thereof, the bottom plan view being a mirror image thereof;

FIG. 3 is a left side elevational view thereof; and,

FIG. 4 is a right side elevational view thereof.

In the drawings, the broken lines in FIG. 1 depict portions of environment that form no part of the claim.
